Des. 216,879
Patented Mar. 17, 1970

216,879

PORTABLE LOUNGE SEAT

David J. Petersen, 1206 Thomas Lane 98498, and Bruce S. Martin, 2224 N. Puget Sound 98406, both of Tacoma, Wash.

Filed Apr. 2, 1968, Ser. No. 11,257

Term of patent 14 years

Int. Cl. D6—01

U.S. Cl. D15—11

We claim:

The ornamental design for a portable lounge seat, as shown.
